UNITED STATES PATENT OFFICE.

MAX ADAMSON, OF TULSA, OKLAHOMA, ASSIGNOR TO RAYMOND F. CARR, OF TULSA, OKLAHOMA.

PADLOCK.

Application filed January 10, 1927. Serial No. 160,242.

The invention relates to padlocks of the sliding shackle type and it aims to provide a generally improved and simplified lock of this character in which novel provision is made for limiting the outward sliding of the shackle, the stop means being placed in position from the interior of the lock body during assemblage, whereas ordinarily, a rivet for this purpose is passed through a specially drilled opening in said body.

With the foregoing in view, the invention resides in the novel subject matter hereinafter described and claimed, the description being supplemented by the accompanying drawing.

Figs. 1 and 2 are vertical sectional views partly in elevation illustrating the lock respectively in locked and released positions.

Fig. 3 is a vertical sectional view on line 3-3 of Fig. 1.

Fig. 4 is a horizontal sectional view on the correspondingly numbered line of Fig. 2.

Figs. 5 and 6 are fragmentary sectional views partly in elevation, illustrating the preferred manner of securing the plate which carries the shackle stop.

In the drawing above briefly described, the numeral 7 designates an appropriate body formed of any desired metal. This body is provided with relatively long and short longitudinal bores 8 and 9 to receive the ends 10 and 11 of a shackle 12, said ends having notches 13 and 14 for co-action with bolts, yet to be described.

A cylinder-containing recess 15 is formed in the body 7 and opens through one end thereof, a transverse, bolt-receiving recess 16 is formed in said body between the other end of the latter and the recess 15, a longitudinal opening 17 leads from one recess to the other, and a transverse opening 18 leads from the inner end of the recess 15, to the bore 8. 19 designates two slidable bolts in the recess 16, urged outwardly by springs 20 for co-action with the notches 13 and 14 to lock the shackle 12 in closed position. When assembling the lock, these bolts may be inserted into the recess 16 through an opening 21 in the body 7, the opening being then plugged as indicated at 22.

The end 10 of the shackle 12 is formed with a stop 23 and with a peripheral groove 24 adjacent said stop, and a second, stationary stop 25 is disposed in the outward path of the stop 23 to limit the projection

of the shackle 12, under the influence of the ordinary spring 26. The stop 25 is carried by a plate 27, which plate is within the inner end portion of the cylinder-receiving recess 15. The inner end wall of this recess is counter-recessed at 28 and a portion of the side wall of said recess is grooved as at 29, for the reception of the plate 27. The side wall of the counter-recess 28 is undercut as shown at 30 and the edge of the plate 27 is beveled as at 31. The plate is inserted into position by passing it into the recess 15 and angling it so that it may be inserted into the groove 29 and the stop 25 passed through the opening 18. Then, by means of a punch or the like P (Fig. 6), the plate may be "mushroomed" into tight contact with the undercut wall 30.

The plate 27 is formed with an opening 32 registering with the opening 17 and having a stepped side wall providing an upwardly facing shoulder 33. A cylindrical releasing member 34 for the bolts 19, is rotatably received in the opening 17 and rests upon the shoulder 33 of the plate 27, to be rotatably supported by the latter, said member 34 having upstanding studs 35 operatively related with appropriate shoulders on the bolts 19, for the purpose of releasing them when said member is turned in the proper direction.

A lock cylinder 36 is secured in the recess 15 by an appropriate screw 37. This screw passes through a suitable bore at the lower end of the bore 9 and after insertion, may have its head locked by use of a punch.

A rotatable barrel 38, is disposed in the cylinder 36 and is controlled in the usual way by key and tumblers. The upper end of this barrel projects from the cylinder 36 and is received in the lower portion of the opening 32, and said projecting end is connected with the member 34. To establish this connection, I preferably provide the barrel with a ridge 39 received in a groove 40 in the member 34.

By providing the novel construction shown and described, or a substantial equivalent thereof, a lock is provided which may be easily and inexpensively manufactured, unusual speed being permitted when assembling. Moreover, the lock will be advantageous and exceptionally durable, and its construction is such that it cannot be released by striking any part of the body with

a hammer or the like. To open the lock, the proper key must be inserted into the barrel 38 and the latter turned to withdraw the bolts 19. Then, the spring 26 expands 5 and outwardly slides the shackle 12. This outward sliding is limited by the co-acting stops 23—25 which come in contact with each other when the shackle is at its extreme outward position. At that time, the 10 stop 25 is opposite the groove 24, so that the shackle 12 may be turned to any desired position.

As excellent results are obtainable from the details disclosed, they are preferably 15 followed. However, within the scope of the invention as claimed, variations may be made.

I claim:

1. In a lock, a shackle, a body having a 20 bore slidably receiving one end of said shackle, said body being provided with a recess to receive lock parts and with an opening from said recess to said bore, and a plate mounted in said recess and having a 25 shackle stop projecting through said opening into said bore, said end of the shackle having a stop co-operable with the first named stop to limit the outward movement of the shackle.
2. A lock comprising a body having a 30 longitudinal bore, a cylinder-receiving recess spaced from said bore and opening through one end of the body, a transverse bolt-receiving recess between the other end 35 of the body and the cylinder-receiving recess and communicating with said bore, a

longitudinal opening from one recess into the other, and a transverse opening from the cylinder-receiving recess into the aforesaid bore; a shackle having one end 40 slideable in said bore and provided with a stop, a plate in the inner end of the cylinder-receiving bore having a shackle stop projecting through the aforesaid transverse opening into the outward path of the first named 45 stop, said plate having an opening registering with the aforesaid longitudinal opening, a lock cylinder secured in the aforesaid cylinder-receiving recess, and rotatable bolt-releasing means extending from the cylinder through the registering openings of the body and plate and operatively connected with the above named bolt.

3. A structure as specified in claim 2; the 50 inner end wall of said cylinder-receiving recess being formed with a counter-recess in which said plate is received, said counter-recess having an undercut side wall and the plate being formed with a beveled edge engaged by said undercut side wall.

4. A structure as specified in claim 1; the 55 inner end wall of said recess being formed with a counter-recess having an undercut side wall and the plate being formed with a beveled edge engaged by said undercut side wall.

5. A structure as specified in claim 2; said 60 rotatable bolt-releasing means embodying a section rotatably supported by said plate.

In testimony whereof I have hereunto 65 affixed my signature.

MAX ADAMSON.
